UNITED STATES PATENT OFFICE.

JAMES PICKERELL, OF HOOPESTON, ILLINOIS, ASSIGNOR TO AMERICAN CAN COMPANY, OF NEW YORK, N. Y., A CORPORATION OF NEW JERSEY.

FINGER-GAUGE TRUING DEVICE.

Application filed May 2, 1921. Serial No. 466,316.

This invention relates in general to slitting machines for sheets of tin and the like, and has more particular reference to means for preventing the presenting of irregularly positioned sheets or blanks to cutters employed in the machine.

A principal object of the invention is the provision of an improvement upon the mechanism described in the co-pending application, No. 469,116 filed May 13, 1921, of Luther C. Bachelder, on finger gauge truing device.

More particularly stated, the principal object of the invention is the provision of means for preventing the pushing forward or lifting of one of the gauges or finger members employed in a device of this character prior to the squaring up or truing of the sheet or blank.

20 A further object of the invention is the provision of means for positively holding each of the finger gauges in locked position until the advancing blank has been perfectly aligned with respect to the horizontal 25 line of the cutters, thus rendering impossible the failure of said gauges to function as intended.

Numerous other objects and advantages of the invention will be apparent as it is 30 better understood from the following description, which, taken in connection with the accompanying drawings, discloses a preferred embodiment thereof.

Referring to the drawings:

35 Fig. 1 is an elevational view in broken section of a part of a slitting machine upon which my invention is employed;

Fig. 2 is a detail section taken substantially on the line 2—2 of Fig. 1;

40 Fig. 3 is an enlarged section taken substantially on the line 3—3 of Fig. 1.

Fig. 4 is a similar view showing the finger members in unlocked or clearance position, such position being indicated by dotted 45 lines; and

Fig. 5 is a perspective view of a device employed to prevent the blank from passing under the gauges without tripping them.

Before entering upon a detailed description 50 of the operation of my invention I will give a brief explanation of the operation of slitting sheets of tin into can body blanks. It is the general practice in can factories to cut can body blanks from large

sheets, which are procured from the tin 55 plate mills, of nominal overall dimensions. The large sheets are taken to a trimming slitter and passed through properly adjusted slitting cutters that act to trim two opposite edges of the large sheet and slit them 60 in one or more sections, each section having a width equal to can body length; these slit sheets are then taken in packs to the can body slitter and, where hand feeding is employed, the top sheet of the pack is removed 65 from the pack on to the slitter feed table through the flat of the operator's hand resting on the sheet, when it is rapidly placed against the ordinarily used fixed guide 70 gauge which gives the sheet proper lateral adjustment, and it is then pushed through the slitting cutter and cut up into can body blanks. When using only the fixed side gauge for gauging the blanks it is necessary 75 that some kind of a truing or gauging device be employed for contacting with the front edge of the sheet in order to bring that edge into exact parallelism with the axes of the slitting cutters so that the body 80 blanks cut from the sheet are square and true. My improvement to the Bachelder device accomplishes this desirable result in a very effective and positive manner as will be fully described in the following specification.

Upon the drawings employed for the purpose of illustrating my invention, I have shown in outline a table 11 of a slitting machine, this table serving as a support 90 also for the mechanism of my invention. At the ends of this table are brackets 12 having at their upper ends bearings 13 for a bar or rod 14, which is free to rotate therein except as otherwise restrained. Fixed 95 upon the rod 14 at intervals are hubs 15 to which are rigidly secured finger gauges 16 having their lower ends 16' protruding downwardly and in front of the table 11, it being understood that the tin sheets or blanks are moved in any preferred manner over this table to cutter members 17, which in this instance, are shown as of circular configuration, and mounted upon slitter shafts 18 and 19.

The generally used fixed guage bar at the side of the slitter feed table is used in the operation of my invention and is necessary to bring the sheets into proper lateral ad-

justment so that the untrimmed edges of the sheet will be trimmed when the sheets are cut into body blanks. It might also be noted here that the slitter cutter heads are 5 provided with feed rolls 10 which engage the sheet as soon as they are presented and automatically carry them through the slitter against the resistance of the slitter cutters. The lower rolls 10^a which cooperate with the 10 upper rolls 10 in the usual manner to grasp and advance the sheet are shown in Fig. 4. The position of the brackets 12 is such that the rods 14 and the finger gauges 16 are located in front of the cutters, viewed from 15 the position from which the sheets are advanced, and the lower ends 16' of the gauges are normally positioned between the cutters and at the sides of the cutting edges.

Rigidly secured to the rod 14 and adjacent each of the finger gauges are locking bars 21, these bars being also secured by means of bolts 22 to the hub members 15, it being noted that both of these parts are fast upon the rod 14. Locking fingers 23 are provided adjacent each of the finger gauges and are pivoted at 24 to ears 25 protruding from a guard 26 which is attached by means of screws 27 to the bracket 12. The upper end 28 of the locking member 23 is squared and adapted to fit in a cut-out or recess 29 in the bar 21. A spring 31, secured at one end to the member 23 and at the other to the bar 21, is adapted to normally maintain the member 23 in locked 20 position, i. e., with the end 28 engaged in the recess 29, the member being so shaped that when in such position its lower end 32 is disposed slightly to the rear of the lower end 16' of the finger gauge 16. (Fig. 3.) A 25 forked member 33 is secured by means of screws 34 to the under side of the table 11, and has its forked end bent upwardly, as at 34 (Fig. 5), and extending slightly above the level of the table and between adjacent 30 cutters 17. The lower ends of the finger gauge 16 and locking member 23 operate in a slot 35 of this forked member, and the forward portion 35' serves to prevent the 35 passage of the sheets beneath the gauges without tripping them.

Referring now to Figs. 1 and 2, it will be noted that I have provided a bored lug 36 having a collar 37 fast on the rod 14. Extending through the aperture in the lug is a 40 pin 38 having a collar nut 39 at its lower end, and a spring 41 jacketed upon it and bearing upwardly against the lug 36. A projection or flange 42 extends out from the support 12 into position immediately above the lug 36 and the pin 38 has screw threaded engagement at one end therewith. A bolt 43 is threaded through this flange from the top and its lower end 44 serves as a stop for the upwardly pressed lug 36. The 45 purpose of this arrangement, as will pres-

ently appear, is to offer yielding resistance to rotary movement of the rod 14 when pressure is exerted against the fingers 16 by the advancing blanks and a positive limitation, by the bolt 43, to the downward and rearward swinging of the fingers 16.

The action of this device may be seen by reference to Fig. 4 in which the unlocked position of the parts is shown in dotted lines. It is evident that the rod 14 cannot be rotated so long as the locking member 23 is engaged in the recess 29, and that this locking member is released from such locking engagement by the advancing sheets upon the table prior to their contact with the finger gauge 16. It will also be understood that one of these locking devices is associated with each of the finger gauges and that they are independently effective to prevent rotation of the rod. It, therefore, requires simultaneous release of these members to permit the rod to be rotated by pressure exerted by the sheets against the fingers 16, and such release cannot be effected unless the sheets be aligned. If both locking devices are released at once and the finger gauges simultaneously operated, it proves that the sheet is squared up or aligned, and unless the locking devices are simultaneously released the sheets cannot advance to the cutters. My device is, therefore, automatic in its action and positively prevents the presenting of an irregularly positioned blank to the cutters.

It has been my experience in the operation of slitters having finger gauges of the Bachelder type as referred to that occasionally an operator will push the sheet through the machine so rapidly and with so much force that the gauges will be moved before the sheet has been properly placed in contact with both of the finger gauges resulting in inaccurate cutting of the body blanks. To overcome this occasional mis-gauging of the sheet is the principal object of this invention.

This device is complete in itself and may be employed alone or in conjunction with the construction described in the co-pending application of Luther C. Bachelder, above referred to.

While my invention, of itself, provides effective means for accomplishing the objects hereinabove specified, it has been found especially advantageous to employ it together with the Bachelder device, in which event it is practically impossible to advance a blank to the cutters in irregular or unaligned position.

It is thought that the invention and many of its attendant advantages will be understood from the foregoing description, and it will be apparent that various changes may be made in the form, construction and arrangement of the parts without departing from the spirit and scope of the invention.

or sacrificing all of its material advantages, the form hereinbefore described being merely a preferred embodiment thereof.

In addition to its use in slitting machines 5 it will be understood that my improvement may be employed in scoring machines for which it is adapted.

I claim:

1. In a slitting machine, means for cutting 10 sheets of tin and the like, and means for aligning the sheets with respect to said cutting means, said aligning means comprising a plurality of aligned finger gauges connected and movable together and disposed in the path of and operable by the sheets as they are advanced to the cutting machines, and removable from said path only when simultaneously operated, and means releasable by the sheet for locking said finger gauges.

2. In a slitting machine, means for cutting 15 sheets of tin and the like, and means for aligning the sheets with respect to said cutting means, said aligning means comprising a plurality of aligned finger gauges connected and movable together and disposed in the path of and operable by the sheets as they are advanced to the cutting machines, and means associated with said gauges for preventing their movement from said path except when simultaneously operated.

3. In a slitting machine, means for cutting 20 sheets of tin and the like and means for aligning the sheets with respect to said cutting means, said last mentioned means comprising aligned members obstructing advance of said sheets to said cutting machines, means for locking said members in obstructing position and for maintaining them in such position except in the event that they are simultaneously operated by the advancing sheets.

4. In a slitting machine, means for cutting 25 sheets of tin and the like and means for aligning the sheets with respect to said cutting means, said aligning means comprising finger gauges disposed in the path of movement of the sheets toward the cutting means, a rotatable member to which said gauges are rigidly secured, means for yieldingly opposing rotation of said member and means for positively locking said member against rotation and thereby preventing movement of the finger gauges except in the event that pressure is simultaneously applied to said gauges.

5. In a slitting machine, means for cutting 30 sheets of tin and the like and means for aligning the sheets with respect to said cutting means, said aligning means comprising supporting means, a rotatable member having bearings in said supporting means, a device for yieldingly opposing rotary movement of said member, aligned finger gauges rigidly mounted upon said member and each

having an end disposed in the path of the sheets as they are moved to said cutting means, said ends being movable from said path only through rotation of said member, and means associated with each of said finger gauges for preventing such rotation unless said gauges be simultaneously operated.

6. In a slitting machine, means for cutting 35 sheets of tin and the like and means for aligning the sheets with respect to said cutting means, said aligning means comprising a plurality of finger gauges disposed in the path through which the sheets are moved to the cutting means, means whereby the advancing sheets may move said gauges from said path and independent locking means associated with each gauge whereby its movement is prevented except simultaneously with the others.

7. In a slitting machine, means for cutting 40 sheets of tin and the like and means for aligning the sheets with respect to said cutting means, said aligning means comprising a plurality of finger gauges disposed in the path through which the sheets are moved to the cutting means, means whereby the advancing sheets may move said gauges from said path and independent locking means associated with each gauge whereby its movement is prevented except simultaneously with the others whereby to insure alignment of the sheets prior to their advance to the cutting means.

8. Means for aligning or truing the edges 45 of moving articles with respect to a given line, comprising aligned finger gauges connected and movable together and disposed in the path of the articles and removable therefrom only by simultaneous contact of said articles with each of said gauges.

9. Means for aligning or truing the edges 50 of moving articles with respect to a given line, comprising aligned finger gauges disposed in the path of the articles and removable therefrom by the pressure of said articles and independently releasable locking devices associated with each of said gauges and requiring simultaneous release to permit further advance of said articles.

10. Means for aligning or truing the edges 55 of moving articles with respect to a given line, comprising aligned finger gauges disposed in the path of the articles and removable therefrom by the pressure of said articles and independently releasable locking devices associated with each of said gauges and requiring simultaneous release to permit further advance of said articles, such release being effectible only by an aligned article.

11. The combination with sheet-feeding 60 means and cutting means, of a plurality of sets of aligning devices for temporarily retarding the advance of the sheet to said feeding devices for the purpose of aligning the

same, one of said sets acting before the other on the front part of the sheet.

12. The combination with sheet-feeding means and cutting means, of a plurality of sets of alining devices for temporarily retarding the advance of the sheet to said feeding devices for the purpose of alining the same, one of said sets acting before the other on the front part of the sheet and 10 one of said sets maintaining engagement with the sheet until it is held by said feeding means.

13. In a machine for gauging and cutting large sheets of tin into accurately dimensioned can body blanks, comprising slitting cutters and feed rolls, movable aligning means for accurately aligning sheets of tin in relation to said slitting cutters and feed rolls, and movable locking means controlling 20 the movement of said aligning means, said aligning and said locking means being operated through the movement of a sheet of tin contacting therewith only when said sheet is in accurate alignment.

25. 14. In a machine for gauging and cutting large sheets of tin into accurately dimensioned can body blanks, comprising slitting cutters and feed rolls, movable aligning means for accurately aligning sheets of tin in relation to said slitting cutters and feed rolls, and movable locking means controlling the movement of said aligning means, said aligning and said locking means being operated through the movement of a sheet of tin 30 contacting therewith, only when said sheet is in accurate alignment, said aligning and locking means contacting and moving with said sheet until the same is engaged and in the control of said feed rolls and 35 slitting cutters.

40. 15. In a machine for gauging and cutting large sheets of tin into accurately dimensioned can body blanks, comprising slitting cutters and feed rolls, movable spring controlled aligning means for accurately aligning sheets of tin in relation to said slitting cutters and feed rolls, and movable spring controlled locking means controlling the movement of said aligning means, said aligning and said locking means being operated 45 through the movement of a sheet of tin contacting therewith only when said sheet is in accurate alignment.

50. 16. In a machine for gauging and cutting large sheets of tin into accurately dimensioned can body blanks, comprising slitting cutters and feed rolls, movable aligning means for accurately aligning sheets of tin in relation to said slitting cutters and feed rolls, said aligning means normally resting 55 in front of said slitting cutters and feed rolls, and movable locking means normally lying in advance of said aligning means, said locking means being operated through the 60 contact of an advancing sheet before move- 65

ment of said aligning means will be permitted after which both said aligning means and said locking means will move in unison with said advancing sheet until said sheet is in contact with said feed rolls and said slitting cutters. 70

17. In a machine for gauging and cutting large sheets of tin into accurately dimensioned can body blanks, comprising slitting cutters and feed rolls arranged in opposed pairs, aligning means normally locked against movement and resting at one side of a plane passing through the axes of said pairs of cutters and feed rolls, and locking means normally holding said aligning means against movement resting to the rear of said aligning means, so that an advancing sheet of tin will first engage said locking means thus releasing contact with said aligning means, then engage said aligning means, and then by continued movement carry said locking means and said aligning means to a position on the opposite side of said plane, said sheet holding the said locking and aligning means in said position on the opposite side of said line during its passage through said machine. 80

18. In a machine for gauging and cutting large sheets of tin into accurately dimensioned can body blanks, comprising slitting cutters and feed rolls arranged in opposed pairs, spring controlled aligning means normally locked against movement and resting on one side of a plane passing through the axes of said pairs of cutters and feed rolls, spring controlled locking means normally holding said aligning means against movement and resting in the rear of said aligning means so that an advancing sheet of tin 90 will first engage said locking means thus releasing contact with said aligning means, then engage said aligning means, then by continued movement carry the said locking means and said aligning means to a position opposite of said plane, and maintain 95 the said aligning and said locking means in said position until the said sheet has passed through and out of the said machine. 100

19. Means for aligning or gauging the edges of moving articles with respect to a given line, comprising aligned gauges disposed in the path of advancing articles, locking means engaging said aligned gauges and disposed in the path of said advancing articles, whereby said advancing articles will 110 first engage said locking means releasing the same from said aligned gauges and then engage said aligned gauges and move said gauges and locking means out of their path as they continue their advance. 115

20. In combination with means for the feeding of articles to an operating mechanism, a plurality of sets of gauging and aligning devices for accurately aligning said articles until within the control of said feed- 120

ing means and locks for holding the later acting of said devices one of said sets acting in advance of the other and having means for releasing said locks, to insure the perfect functioning of said other set.

21. In a sheet cutting machine a gauging means comprising a pair of gauging elements connected and operated together to arrest the sheet and turning together out of the path of the sheet after it has been

gauged, and a pair of independently movable elements which are operable independently and successively to arrest the sheet and also to align the sheet prior to its contact with the first mentioned gauging elements, each of the independent gauging elements having means for preventing the movement of both of the connected gauge elements. 15

JAMES PICKERELL.
